H. F. SCHENUIT.
ZITHER PIANO.

1,238,718.

Patented Aug. 28, 1917.

UNITED STATES PATENT OFFICE.

HENRY F. SCHENUIT, OF PASADENA, CALIFORNIA, ASSIGNOR OF ONE-HALF TO MARIE SEBASTIAN WUSTUM, OF PASADENA, CALIFORNIA.

ZITHER-PIANO.

1,238,718.

Specification of Letters Patent. Patented Aug. 28, 1917.

Application filed December 19, 1916. Serial No. 137,833.

To all whom it may concern:

Be it known that I, HENRY F. SCHENUIT, a citizen of the United States, residing at Pasadena, in the county of Los Angeles and 5 State of California, have invented new and useful Improvements in Zither-Pianos, of which the following is a specification.

This invention relates to zithers and particularly pertains to keyed zithers or zither 10 pianos.

It is an object of this invention to provide a zither piano which has a piano key action with dampers and adapted to be actuated in the same manner as a regular piano and with 15 the same rapidity of movement so that the tones obtained by striking the keys will be clear and susceptible to modulation by the player.

Another object is to provide means for 20 individually picking the strings of the zither and damping the action, thus permitting the operation to be continued with any desired rapidity without destroying the effect of the individual tones produced.

Another object of this invention is to 25 provide a key mechanism and a string picking device which act in combination in a direct manner without the embodiment of complicated mechanism in their construc- 30 tion.

Another object of this invention is to provide simple damper means adapted to be 35 actuated simultaneously with the depression of a key and to be restored instantly upon the release of a key.

Another object is to provide an arrangement of the string picking members so that the strings may be arranged in close relation to each other thereby producing a compact 40 musical instrument.

Another object of this invention is to provide simple and direct acting forte control means.

Other objects will appear hereinafter.

45 The invention is illustrated, by way of example, in the accompanying drawings in which:

Figure 1 is a view in vertical cross section as seen through a zither piano constructed 50 according to the spirit of the present invention and particularly discloses the key and damper mechanisms.

Fig. 2 is a fragmentary view in plan illustrating a group of zither strings mounted 55 upon a sounding board and fitted with keys

and actuating mechanism whereby each of said strings may be individually picked.

Fig. 3 is a view in vertical section and elevation illustrating one of the zither-picking elements.

Fig. 4 is a vertical cross-section on the lines 4—4 of Figs. 1 and 2, of the actuating mechanism by which the forte of the zither piano is controlled, the dampers being normally down upon the strings and adapted 65 to be raised simultaneously from the strings by the knee of the operator.

Fig. 5 is a view of a modified form of the pick bar and a mounting for the obliquely disposed washer.

Referring more particularly to the drawings, 10 indicates a zither piano case which is formed in the conventional shape of a grand piano. This case is fitted with a bottom board 11 suitably perforated with openings 12 to permit sound vibrations to pass from a sounding board 14 mounted within the case and above the board 11. This board is of a desired and suitable shape to accommodate zither strings 15 which are adjustably held thereover and bridge the sounding board between transverse bridge strips 16 and 17. The ends of the strings are secured at the forward end of the zither piano upon pins 18 while the opposite ends are adjustably secured upon tuning pins 19. Due to the compact arrangement of the string picking mechanism these strings may be arranged in close relation to each other and a wide range of tone obtained from the zither 90 piano.

The strings are indirectly caused to vibrate by striking keys 20 which are arranged upon the key-board of a zither piano and are adapted to be actuated in the same manner as a regular piano. These keys extend over the sounding board and are supported intermediate their lengths upon a fulcrum rail 21 upon which a felt pad 22 is positioned to support the keys. A pin 23 extends upwardly through the fulcrum rail 21 and the key and permits it to have pivotal movement. The forward end of the key is formed with a counterbore 24 into which a guide pin 25 extends to center each key individually. 105 The guide pin 25 extends upwardly through a felt cushion strip 26 by which the impact of the keys is absorbed. The rear end of each key is fitted with an adjustable rocker 27 secured and longitudinally adjusted on 110

the key by a bolt 28', extending through slot 28 and adjusted in vertical relation thereto by means of an adjusting screw 29. Mounted upon the end of each rocker is a pick bar 30 which stands vertically and is held by means of a screw 30' which extends into the end of the rocker and holds the bar against a felt pad 31 interposed between the end of the rocker and the side of the pick bar. A leaf spring 32 is positioned beneath the head of screw 30' and holds the bar against the rocker in a yieldable manner, although it is evident that a coil spring might be used to advantage. A locating pin 32a holds each spring 32 against lateral movement. Attention is directed to the fact that the pick bars are staggered in relation to each other by means of alternate extensions upon the rockers and in this manner may be arranged compactly over a sounding board. Each of the pick bars is formed with an upper end having a diagonal face upon which is fixed an oblique leather plate 33. This plate extends from the side of the pick bar and is fitted with an oblong opening 34 through which a guide rod 35 extends. This rod is held by means of a screw to a transverse guide strip 36 which extends the width of the sounding board. Adjustably fixed upon each of these guide rods above the plates 33 is a trip finger 37 held by a set screw 38 and adapted to be engaged by the plate 33 to actuate the pick bar to return it to its lowermost position without striking the string or interfering with its vibration. Adjustably fixed upon each of these guide rods 35 below the plate 33 is a trip finger 37' held by a set screw 38', similar to finger 37 and screw 38, and adapted to be engaged by the plate to actuate the pick bar 30 to its normal position after the pick has passed downwardly beyond the string so that the pick will be ready to strike the string at the next impulse. The tension and friction is sufficient to hold the pick bar until positively moved by the finger 37 or 37'. A guide strip 39 is positioned parallel to the strip 36 and supports a series of guide rods 35 adapted to guide the staggered pick bars. Brackets 40 are secured to the guide strip 39 and support a bar 40' carrying guide pins 41 which extend downwardly.

Reference being had to Fig. 5 of the drawings, it will be seen that the pick bar 30 is formed with an oblique groove in which the end of the plate 33 is fitted and glued. In this manner the pick bar construction might be greatly simplified, if desired. A pin 65 aids in holding the plate in place.

The damper mechanism is comprised of a series of actuating bars 42 which have felt pads 43 extending along their opposite sides and adapted to bear against guide pins 41 which are positioned between the bars. A pivot pin 45' secures each damper bar

by a flange 45 to a rail 46 which in turn is pivoted by means of pin 47 to standards 48 disposed at the opposite ends of the sounding board or at the ends of the treble and bass clef. The flange is rigidly held on the rail by a suitable screw. Adjustably secured upon each bar 42 by means of a screw 49 is a damper block 50 upon which a felt pad 51 is mounted to bear upon the string. The damper bars are actuated by means of damper lifters 52 which are secured at the end of each of the keys 20 and extend rearwardly beneath the forward end of their corresponding damper bar. A felt strip 53 is interposed between the end of the bar 42 and its lifter 52.

As a means for lifting the damper pads 51 from the strings, a lever 54 is vertically mounted to project below the case by means of a hinge 55 and is adapted to be actuated by the knee of the operator. When this lever is moved it transmits movement through a push rod 56 to a crank arm 57 and from the crank arm through the rock-shaft 66 to a crank arm 67 acting beneath an elevating rod 58 which in turn bears beneath the block 46 of the dampers within a counterbore 58' and raises them entirely from the strings. The spring 56' returns the actuating parts to normal position. This mechanism does not affect the strings producing the notes from E-flat to B-flat, inclusive, above the middle C. The dampers on these strings are only raised when the keys are actuated as it has been found in practice that it is impractical to play forte upon these strings, due to the fact that they are liable to produce harsh and shrill notes, which is obviated by the damping effect of the dampers.

When the zither is to be played, the keys are depressed, as is common in all piano actions, and they will pivot upon the pin 28 to be elevated at their rear ends. This action will, at the same time, raise the rocker 110 mounted upon the end of the particular key and this will in turn move the pick bar upwardly in a substantially vertical line, at the same time causing a pick 59 rigidly secured at the lower end of the bar by screws 60 115 to pluck the string, and as the nose of the pick passes upwardly by the string the oblique plate 33 will move upwardly and engage the finger 37 mounted upon the vertically extending guide rod 35. This action 120 will cause the pick bar to swing in the direction of the arrow —a— upon the supporting screw 30' and when the key is released the pick will pass by the string without coming in contact with it. The pick 59 is cut 125 out on one side so that it will clear the lifter 52.

At the same time the key is being depressed, the lifter 52 will move upwardly and lift the damper bar 42 and this in turn will 130

lift the pressure of the damper pad 51 from the string, thereby causing a clear tone to be made when the string is plucked by the pick. It will be seen that as the key is released the lifter 52 will fall to its lowermost position due to the weight of lead lugs 64 and permit the damper bar and the damper pad to return to their normal position, at which time the tone will be damped.

10 When volume is to be obtained from the instrument, the lever 54 may be swung upon its hinge in the direction of the arrow —*b*— and will in turn lift the damper pads 51 from all of the strings, producing an effect 15 which will be readily understood.

It will thus be seen that the piano key action here provided for use with a zither musical instrument is complete, constructed of few parts, readily adjusted and easily 20 actuated and that the action of the keys will be light and may be repeated with great rapidity without impairing the quality of tone produced by the strings.

While I have shown the preferred construction of my zither piano as now known to me, it will be understood that various changes in the combination, construction, and arrangement of parts may be made by those skilled in the art without departing 30 from the spirit of my invention.

I claim:

1. In a zither piano, a sounding board, zither strings upon the sounding board, a rail mounted to swing up and down across 35 and above the strings, damper bars pivotally connected to the rail, dampers adjustably connected to the damper bars, keys mounted above the zither strings and supporting the free ends of the damper bars, so 40 as to raise the dampers one at a time by the operation of the keys, and means for raising the rail so as to raise all of the dampers at once.

2. In a zither piano, a sounding board, 45 zither strings upon the sounding board, a rail mounted to swing up and down across and above the strings, damper bars pivotally connected to the rail, a bar mounted above and across the free ends of the damper bars, guide pins extending downwardly 50 from the bar between the damper bars, dampers adjustably connected to the damper bars, keys mounted above the zither strings and supporting the free ends of the 55 damper bars, so as to raise the dampers one at a time by the operation of the keys, and means for raising the rail so as to raise all of the dampers at once.

3. In a zither piano, a sounding board, 60 zither strings upon the sounding board, a rail mounted to swing up and down across and above the strings, damper bars pivotally connected to the rail, dampers adjustably connected to the damper bars, keys 65 mounted above the zither strings and sup-

porting the free ends of the damper bars, so as to raise the dampers one at a time by the operation of the keys, an elevating rod extending downwardly from the rail through the sounding board, a rock-shaft mounted 70 below the board, an arm connecting the rock-shaft to the elevating rod, and means for operating the rock-shaft by the knee of an operator so as to raise all the dampers at once.

4. In a zither piano, a sounding board, zither strings upon the sounding board, a rail mounted to swing up and down across and above the zither strings, damper bars pivotally connected to the rail, dampers 75 adjustably connected to the damper bars, keys mounted above the zither strings and supporting the free ends of the damper bars, so as to raise the dampers one at a time by the operation of the keys, an elevating 80 rod extending downwardly from the rail through the sounding board, a rock-shaft mounted below the board, an arm connecting the rock-shaft to the elevating rod, a second arm upon the opposite end of the 85 rock-shaft, a spring for holding the second arm to yieldingly hold the dampers depressed, a lever vertically and pivotally mounted and adapted to be operated by the knee of an operator, and a connection be- 90 tween the lever and the second arm; so that by operating the lever all the dampers may be raised at once, and by releasing the lever the spring will return the dampers to their 95 normal position.

5. In a zither piano, a sounding board, zither strings upon the sounding board, a rail mounted across and above the strings, 100 damper bars pivotally connected to the rail, dampers adjustably connected to the damper bars, and keys mounted above the zither strings and supporting the free ends of the 105 damper bars, so as to raise the dampers one at a time by the operation of the keys.

6. In a zither piano, a sounding board, 110 zither strings upon the sounding board, a rail mounted across and above the strings, damper bars pivotally connected to the rail, a bar mounted above and across the free ends of the damper bars, guide pins extending 115 downwardly from the bar between the damper bars, dampers adjustably connected to the damper bars, and keys mounted above the zither strings and supporting the free ends of the damper bars, so as to raise 120 the dampers one at a time by the operation of the keys.

7. In a zither piano, a key, a rocker adjustably mounted upon the key, a pick bar, a spring, and a screw inserted through the 125 spring and pick bar into the end of the rocker to hold the pick bar frictionally pivoted.

8. In a zither piano, a key, a rocker adjustably mounted upon the key and having 130

a flat vertical end face, a pick bar, a cushion between the pick bar and the end face, a spring carried by the pick bar, and a screw inserted through the pick bar and engaging 5 the spring and adjustably mounted in the end of the rocker so as to pivot the pick bar in a substantially vertical position and under a desired amount of friction.

9. In a zither piano, a key, a rocker adjustably mounted upon the key, a pick bar frictionally connected against the end of the rocker, a vertical guide rigidly mounted, two fingers upon the guide, one above the other, and an inclined plate fixed upon 15 the pick bar between the fingers; so that when the pick bar goes up the plate will hit a finger and tilt the pick bar one way, and when the pick bar goes down the plate will hit the other finger and tilt the pick 20 bar the other way.

10. In a zither piano, a sounding board, zither strings upon the sounding board, a rail mounted across and above the strings, damper bars pivotally connected to the rail, 25 dampers connected to the damper bars, keys mounted above the zither strings and supporting the free ends of the damper bars, rockers adjustably mounted upon the keys, pick bars frictionally connected against the

ends of the rockers, vertical guides rigidly 30 mounted, two fingers upon each guide, inclined plates fixed upon the pick bars and between the fingers, and picks upon the pick bars; so that when a key is operated, the corresponding damper will be lifted, and 35 the pick will engage the string and pass upwardly and be tilted out of engagement with the string and pass downwardly and be tilted back into normal position ready for the next operation. 40

11. In a zither piano, a sounding board, zither strings upon the sounding board, a rail mounted to swing up and down across and above the strings, damper bars pivotally connected to the rail, dampers connected to the damper bars, keys mounted above the zither strings and supporting the free 45 ends of the damper bars, so as to raise the dampers one at a time by the operation of the keys, rockers adjustably mounted upon 50 the keys, pick bars frictionally mounted upon the rockers, means for tilting the pick bars, and means adapted to be operated by the knee of an operator so as to raise all the dampers at once. 55

In testimony whereof I have signed my name to this specification.

HENRY F. SCHENUIT.
